RACKET HOLDER

Frederick F. Sprow, San Francisco, Calif.

Application February 24, 1937, Serial No. 127,415

6 Claims. (Cl. 273—74)

This invention relates to holders for rackets, and particularly that type of holder which receives such rackets as are employed in the playing of the game of tennis. The construction of such type of racket is well known and need not be further described, other than to state generally that they are provided with a handle member, at one end of which is a hoop tightly strung longitudinally and laterally with strings of gut or like material which, due to the tension of the strings, is considerably affected by weather conditions, particularly atmospheric humidity. The gut or strings may absorb moisture from the atmosphere or may become moist during playing of a game or in transportation to and from a game, or even in storage, and when the strings contract in drying the hoop becomes warped from its normal plane. Also, if one or more strings are broken during the playing of a game, or even while the racket may be idle or in storage, the tension of the remaining unbroken strings will warp the hoop of the racket from its plane, or even cause it to become radially distorted unless means are employed to prevent such action. For instance, if strings of a racket are broken in play and the racket is laid aside where it may be subject to the rays of the sun or other heat, the hoop will become distorted in a relatively short time. This distortion of the hoop may be in either the normal vertical plane or the normal horizontal plane, or both. Therefore, the need for a convenient racket holder to overcome the aforesaid difficulties will be readily apparent, so that both, or either, of such distortions may be eliminated.

Among the objects of this invention are to provide a racket holder which will prevent warping of the hoop from its planes and maintain the shape of the hoop radially. Another object is to provide a holder for rackets which will accomplish the foregoing objects and is adjustable for holding rackets of varying sizes and shapes and having differing thicknesses of the hoop. Another object is to provide a holder for rackets which is strong, durable, efficient, compact, and light in weight. A still further object is to provide a racket holder having the aforesaid characteristics, and which will be adaptable to accommodate either one or two rackets so that one racket may remain protected by the holder while another racket is in use.

With the foregoing and other objects in view, all of which will be more apparent as this description proceeds, the invention is exemplified in one form in the novel construction and com-

bination of parts hereinafter described, illustrated in the accompanying drawing, and pointed out in the claims hereto appended, it being understood that various changes in the form, proportion, size and details of construction of the apparatus may be resorted to within the scope of the appended claims without departing from the spirit or sacrificing any of the advantages of the invention.

To more clearly comprehend the invention, reference is directed to the accompanying drawing wherein:

Fig. 1 is a perspective view of one form of the invention employed for a single racket.

Fig. 2 is a plan view of the device of Fig. 1. 15

Fig. 3 is a perspective of a modified form of the invention adapted for holding two rackets.

Fig. 4 is a transverse vertical section on line IV—IV of Fig. 3.

Fig. 5 is a fragmentary enlarged section on 20 line V—V of Fig. 3.

Fig. 6 is an enlarged detail in perspective of a form of clamp or gripping member.

Fig. 7 is an enlarged detail in perspective of a clamp or gripping member and a threaded bolt 25 member.

Since the mechanism of movable parts of the devices shown by Figs. 1 and 3 are the same, it is believed that they may be adequately described for both the types of devices by reference to the 30 mechanism of Fig. 4.

Referring to the drawing in which like characters of reference indicate corresponding parts in the several views, 10 indicates a foundation or baseboard which is preferably of greater length 35 than width which may be of any suitable rigid material, but which in the preferred form illustrated in the drawing comprises a laminated structure of relatively thin sheets of wood 11 in which the grain of abutting layers is arranged 40 angularly to the next abutting sheet or layer of material. These layers are securely fastened together by suitable means such as glue, forming a compact, strong, rigid board. The exact shape of the plane of the board is more or less immaterial, and it is to be understood that the shape thereof is not limited to the illustration of the one preferred form shown in the drawing hereof.

Regardless of the shape of the plane of the board, it will have four quadrants, a, b, c, and 50 d, from its central radial point. At the edge of the board in each of these quadrants are clamps or gripping members 12, 13, 14, and 15. The gripping members 12, 13 at one end of the board are angle-iron members, one arm of which is 55

fixedly attached to the board by screws 16. At the opposite end of the board in the adjoining quadrants *c*, *d*, there are recesses 17, 18 which are closed at the surface of the board by plates 19, 20 which are fixedly secured to the board by screws 21. The inner face of the plates 19, 20 have affixed thereto threaded stud-bolts 22, 23, the threaded portion of which extends substantially radially outwardly from the plate and the baseboard 10. Upon these bolts 22, 23, are slidably mounted the gripping members 14, 15, the bolts 22, 23, passing through the openings 24 of these gripping members. The gripping members 14, 15 are also of angle-iron construction, one arm of which, 25, is adapted to slide within the recesses 17, 18. It is preferred that a terminal portion 25^a of the arms 25 shall be inset at its edges as at 25^b whereby the gripping member may be partially pulled out of the recess and the clamp portion 15 rotated on the bolt 23, so that the clamp portion 15 lies substantially on a level with the vertical plane of the baseboard, as best shown in the dotted lines of Fig. 1. By this means the insertion of a racket in the holder is greatly facilitated without too great an extension of the gripping members 14, 15. In the operation of the device it is preferred that one of the adjustable gripping members, preferably 14, in the lower left quadrant of Fig. 1, shall be employed for permanent adjustment purposes, that is, it may be adjusted to a particular point to suit a particular racket and remain at that adjusted position. It is preferred that the other adjustable gripping member 15 in the adjoining lower right hand quadrant of Fig. 1 be a clamp adjustable for use each time that a racket is placed in or taken from the holder. Therefore, means are provided at the member 14 for adjusting it radially inwardly or outwardly to a relatively permanent adjusted position, such means being the knurled finger grip member 26 threadedly mounted on bolt 23, whereas the means for similarly adjusting the operative clamp member 15 is preferably a wing-nut 27. All of the gripping members or clamps 12, 13, 14, 15 extend from the baseboard in a direction substantially perpendicular to the plane of the board, and each of them is formed inwardly at the free end which is spaced from the board, so that the face of a racket hoop may be engaged thereunder.

It is therefore to be noted that by disposing the clamping members in the four quadrants with the adjustable clamp members 14, 15 on stud bolts which are substantially radial to the board, the radially inward pressure from these adjustable clamp members is in the direction of all three of the other clamps, firstly toward the diagonally opposite clamp, secondly, toward the laterally opposite clamp, and thirdly, toward the longitudinally opposite clamp; also, that as the adjustable clamp members are tightened against the hoop, the outer face of the hoop is simultaneously forced under the inwardly turned free end portion of the clamps so as to clamp the other face of the hoop against the board.

In the modification illustrated in Figs. 3 and 4, the clamps are on both sides of the baseboard 10 and the free or clamping ends thereof extend in relatively opposite directions substantially perpendicular to the plane of the board. The holder is substantially a doubling of that shown by Fig. 1, and the boards are placed back-to-back and secured together by suitable means,

such as glue. In this modification it is to be understood that the board may, if desired, be made somewhat thicker than the board of Fig. 1, but not necessarily twice as thick. The recesses 17 and 18 in Fig. 4, and the accessory plates 19, 20, as well as the clamps or gripping members 14, 15, stud bolts 22, 23, and the nuts 26, 27 are of the same mechanical construction as in Fig. 1. The only addition to the mechanical structure is the interposition of a plate 29 between the recesses 17, 18 for the opposite sides of the board. The plate 29 is inset at its side edges into the side walls of the recess and is secured in place by the screws 21 passing therethrough, as best shown in Fig. 5.

From the foregoing description it is believed that the operation is apparent. Having accomplished a proper relatively permanent adjustment of the gripping member 14, the racket is placed in the holder with one face of the hoop overlying the baseboard. In order to readily insert the racket the gripping member 15 may be turned or rotated sidewise on the bolt 23 as shown in dotted lines of Fig. 1, and may be returned to its clamping position after the racket is inserted. The wing-nut 27 may then be tightened to clamp the racket in the holder. The forming over of the free ends of the gripping members 12, 13, 14, 15 is preferably not at a right angle, but is more or less arcuate so as to accommodate and securely grip racket hoops of varying thickness.

Having thus described my invention, I claim:

1. A holder for rackets comprising a baseboard adapted for receiving one face of a racket in relatively overlying relation, gripping members mounted at the four quadrants of the baseboard and extending therefrom in a direction perpendicular to the plane thereof and each including means spaced from the baseboard for engaging the racket hoop at its opposite face, a portion of said gripping members being movably mounted for movement substantially radially inwardly and outwardly relative to the baseboard, and means for clamping said movable gripping member against the hoop of a racket in the holder.

2. A holder for rackets comprising a baseboard adapted for receiving one face of a racket in relatively overlying relation and having a recess at a quadrant edge thereof, gripping members mounted at the four quadrants of the baseboard and extending therefrom in a direction perpendicular to the plane thereof and each including means spaced from the baseboard for engaging the racket hoop at its opposite face, a portion of said gripping members being movably mounted in said quadrant recess and adapted for movement substantially radially inwardly and outwardly relative to the baseboard and means for clamping said movable gripping member against the hoop of a racket in the holder.

3. A holder for rackets comprising a baseboard adapted for receiving one face of a racket in relatively overlying relation and having recesses at quadrant edges thereof, a plate overlying each recess, gripping members mounted at the four quadrants of the baseboard and extending therefrom in a direction perpendicular to the plane thereof and each including means spaced from the baseboard for engaging the racket hoop at its opposite face, a portion of said gripping members being movably mounted in said quadrant recesses for movement radially inwardly and outwardly relative to the baseboard, and means

for clamping said movable gripping member against the hoop of a racket in the holder.

4. A holder for rackets comprising a baseboard adapted for receiving one face of a racket in relatively overlying relation and having recesses at 5 quadrant edges thereof, plates overlying said recesses, threaded bolts mounted at said recesses, gripping members mounted at the four quadrants of the baseboard and extending therefrom in a 10 direction perpendicular to the plane thereof and each including means spaced from the baseboard for engaging the racket hoop at its opposite face, a portion of said gripping members being movably mounted in said quadrant recesses for movement 15 radially inwardly and outwardly relative to the baseboard and means mounted on said bolt for clamping said movable gripping member against the hoop of a racket in the holder.

5. A holder for rackets comprising a baseboard 20 adapted for receiving one face of a racket in relatively overlying relation and having a recess in each of adjoining quadrant edges of the board, a pair of gripping members at each of the opposite end portions of the baseboard and extending 25 therefrom in a direction perpendicular to the plane thereof and each including means spaced from the baseboard for engaging the racket hoop at its opposite face, the pair of gripping mem-

bers in adjoining quadrants of the board being movably mounted in said quadrant recesses and adapted for movement radially inwardly and outwardly relative to the baseboard and toward and from the diagonally opposite gripping member, 5 and means for clamping said movable gripping members against the hoop of a racket in the holder.

6. A holder for rackets comprising a baseboard adapted for receiving one face of a racket in relatively overlying relation and having a recess in 10 each of two quadrant edges of the board, a threaded bolt mounted at each of said recesses and extending outwardly substantially radially to the board, a pair of gripping members at each 15 of the opposite end portions of the baseboard and extending from the board in a direction perpendicular to the plane thereof, and each including means spaced from the baseboard for engaging the racket hoop at its opposite face, two of 20 said gripping members being mounted on said bolts at said recesses and adapted for movement radially inwardly and outwardly relative to the baseboard and means for clamping said movable gripping members against the hoop of a racket 25 in the holder.
